PATENTED MAR. 24, 1908.

J. D. BAKER.

FRICTION GEARING.

APPLICATION FILED APR. 6, 1907.

2 SHEETS-SHEET 1.

Fig. 1.

lower edges arranged flush with the upper and lower edges of the sides and ends of the support, said support being provided with corresponding upper and lower faces and adapted to be turned over to present the underside to the grate section and to counter-act sagging or warping.

8. A reversible oblong grate section provided at intervals with transverse oblong openings of uniform area at both the top and bottom of the section, said openings forming transverse bars and longitudinal connecting bars arranged at right angles to each other and having horizontal upper and lower faces, 15 said grate section being also provided with side and end spacing lugs located opposite the ends of the transverse and longitudinal bars, and having upper and lower faces ar-

ranged flush with the upper and lower faces of the said bars to form corresponding upper 20 and lower faces to the grate section, whereby the latter is adapted to be turned up-side-down to counter-act sagging or warping and to bring either of the said faces to the bottom, and a support having projecting engaging 25 lugs adapted to fit in any of the oblong openings of the grate section.

In testimony, that we claim the foregoing as our own, we have hereto affixed our signatures in the presence of two witnesses.

UNITED STATES PATENT OFFICE.

JOHN DAVID BAKER, OF LISBON, OHIO, ASSIGNOR OF ONE-THIRD TO ALPHEUS ARTER AND ONE-THIRD TO GEORGE B. HARVEY, OF LISBON, OHIO.

FRICITION-GEARING.

No. 882,861.

Specification of Letters Patent. Patented March 24, 1908.

Application filed April 6, 1907. Serial No. 366,734.

To all whom it may concern:

Be it known that I, JOHN DAVID BAKER, a citizen of the United States, residing at Lisbon, in the county of Columbiana and State 5 of Ohio, have invented a new and useful Friction-Gearing, of which the following is a specification.

This invention relates to friction driving means for automobiles or self-propelled vehicles, but its use is not limited to this type 10 of mechanism, inasmuch as it can be advantageously employed on many machines and mechanisms where change of speed or power is desirable.

15 The principal object of the present invention is to provide novel means of a very simple nature for effecting the frictional engagement between the coacting friction members so as to secure a yielding contact, the force of 20 which can be increased as desired, and a further and important object is to provide improvements in the different details of construction in order to secure a high degree of efficiency in the mechanism as a whole.

25 A further object is to provide in a structure of this character, an adjustable driving disk which is carried by the engine or driving shaft, but which does not require any end-wise movement of the shaft when the disk is 30 adjusted.

The preferred embodiment of the invention is illustrated in the accompanying drawings, wherein:—

Figure 1 is a plan view of the mechanism 35 applied to the frame of a self-propelled vehicle. Fig. 2 is a side elevation of the same. Fig. 3 is a horizontal sectional view there-through. Fig. 4 is a face view of the frame disk. Fig. 5 is a rear view of the same, with 40 a section through the shaft and associated parts on the line 5—5 of Fig. 3. Fig. 6 is a detail sectional view on the line 6—6 of Fig. 3.

Similar reference numerals designate corresponding parts in all the figures of the drawings.

In the embodiment illustrated, a suitable supporting frame 7 is provided, which is provided with spaced cross bars 8. In these cross bars and in the end of the frame, is 50 journaled the usual driving or engine shaft 9. Slidably mounted on the rear end of the shaft 9 is a friction disk 10 having a flat rear friction face 11. The disk is feathered, as shown at 12 to said shaft so that while its 55 sliding movement is not interfered with, it

is held against rotation on the shaft, but is of course rotatable therewith.

A driven shaft 13 is disposed across and contiguous to the friction face 11 of the disk 10, and is provided with a suitable sprocket 63 wheel 14 or other means for transmitting power. On this shaft is loosely journaled a friction wheel 15 that is in frictional engagement with the face 11 of the disk 10 on one side of the axis of rotation of said disk. Another friction wheel 16 is slidable upon the shaft 13, and is movable toward and from the wheel 15, being feathered on the shaft, as shown at 17. The friction wheel 15 is normally in contact with the friction face 11 of the disk, and is movable from the periphery of said disk past the center or axis of movement thereof. This operation is secured by means of a controlling lever 18 having a link connection 19 with a bell crank lever 20. 70 The said lever is provided with a yoke 21 that engages in a groove 22 formed in the hub of the wheel 16. By swinging the lever, it will be evident that the wheel can be moved longitudinally of its shaft 13.

In order to engage and disengage the disk 10 and wheel 16, the following mechanism is employed. A collar 23 is feathered as shown at 23^a on the engine or driving shaft 9, and a lever 24, fulcrumed between its ends, as 80 shown at 25, has a yoke 26 that engages the collar. This lever has a link connection 27 at its outer end with an actuating lever 28. The collar, as shown, is disposed on the opposite side of the cross bar 8 to the disk, and has 85 a sleeve 29, which constitutes a rear journal bearing for the shaft, said sleeve having its rear end slidably mounted on the hub 30 of the shaft and having a flange or shoulder 31 that abuts against the front face of the disk. 90 Draft pins, preferably in the form of headed screws 31^a are slidably passed through the flange 31 and are engaged in the disk 10. It will thus be evident that the collar 23 and sleeve 29 are movable with respect to the 95 disk. A spring 32, housed within the sleeve, has its front end bearing against the rear end of the collar 23, while its rear end bears against the front end of the hub 30 of the disk. Another spring 33 bears against the front 100 end of the collar, and serves to equalize the pressure upon said collar.

The operation of the structure is as follows: If the lever 28 is swung rearwardly, the sleeve 29 will be moved rearwardly upon the shaft 9, 110

able into and out of coaction with the member.

7. In mechanism, of the character set forth, the combination with a shaft, of a friction wheel slidably mounted on the shaft, means for sliding the friction wheel, another shaft disposed at substantially right angles to the first mentioned shaft, a friction disk slidably mounted on the last mentioned shaft and movable into and out of frictional engagement with the wheel, a collar slidably mounted on the latter shaft, means for sliding the collar, a sleeve carried by the collar and having a slidable engagement with the disk, said sleeve and disk having shoulders arranged to abut, a spring located within the sleeve and interposed between the disk and collar, and another spring bearing against the opposite side of the collar to the first mentioned spring.

8. In mechanism of the character set forth, the combination with a shaft held against longitudinal movement, of a disk slidable on one end of the shaft and having an outer friction face, means for sliding the disk longitudinally of and upon the shaft, another shaft disposed across and adjacent to the friction face of the disk, a friction wheel slidable on said latter shaft, and means for sliding the wheel longitudinally of its shaft.

9. In mechanism of the character described, the combination with angularly disposed driving and driven shafts held against longitudinal movement, of a friction disk longitudinally movable on one of the shafts and rotatable therewith, a friction wheel longitudinally movable on the other shaft and rotatable therewith, said friction wheel cooperating with the disk, and means for moving the disk and wheel longitudinally of their respective shafts.

10. In mechanism of the character described, the combination with angularly disposed shafts, each shaft having its axis of

rotation intersecting the axis of rotation of the other shaft, of bearings for said shafts that hold them against lateral and longitudinal movement, a friction disk slidably mounted on one of the shafts, means for moving said disk on its shaft toward and from the other shaft, a friction wheel slidably mounted on said other shaft and coöperating with the disk, and means for moving the friction wheel on its shaft towards and from the axis of the disk.

11. In mechanism of the character described, the combination with an engine shaft, held against longitudinal and lateral movements, of a friction disk slidably mounted on said shaft and held against relative rotation with respect to the same, means for effecting the sliding movement of the disk, a driven shaft disposed transversely of the friction face of the disk and held against lateral movement, a wheel slidably mounted on the driven shaft and held against relative rotation with respect thereto, the periphery of said wheel coöperating with the friction face of the disk, and means for effecting the sliding movement of said wheel.

12. In mechanism of the character set forth, the combination with a friction member of a shaft, a second friction member mounted on the shaft and movable into and out of coöperation with the first-mentioned member, an operating device movable longitudinally of said shaft, a spring interposed between the operating device and second friction member and bearing against one side of the former, and an equalizing spring bearing against the opposite side of the operating device.

In testimony, that I claim the foregoing as my own, I have hereto affixed my signature in the presence of two witnesses.

JOHN DAVID BAKER.
